(57) **CLAIM**

The ornamental design for a cartridge for electronic cutter, as shown and described.

DESCRIPTION

FIG. 1 is a top perspective view of a cartridge for electronic cutter showing our new design;

FIG. 2 is a top plan thereof;

FIG. 3 is a bottom plan thereof;

FIG. 4 is a right side elevation view thereof;

FIG. 5 is a left side elevation view thereof;

FIG. 6 is a rear elevation thereof; and,

FIG. 7 is a front elevation thereof.

The broken line showing of environment in the figure drawings is for illustrative purposes only and forms no part of the claimed design.
